UNITED STATES PATENT OFFICE.

JOHN D. JONES, OF WALLA WALLA, WASHINGTON, ASSIGNOR OF ONE-HALF TO HENRY C. BAKER, OF WALLA WALLA, WASHINGTON.

FAN.

1,226,670.

Specification of Letters Patent.

Patented May 22, 1917.

Application filed April 28, 1914. Serial No. 834,910.

To all whom it may concern:

Be it known that I, JOHN D. JONES, a citizen of the United States, residing at Walla Walla, in the county of Walla Walla and State of Washington, have invented certain new and useful Improvements in Fans, of which the following is a specification.

This invention relates to improvements in fans.

The objects of the invention are, first, to provide a fan and its hub which will by certain minor modifications, be applicable to fans of various types; second, to provide a fan and hub which will be self-lubricating, and of such construction that the customary ball bearings can be disposed with, without experiencing any difficulties, such as the heating of the bearing, wearing of the shaft, etc; third, the provision of a fan and hub by means of which a fan can be rotatably supported on a stationary or non-rotatable shaft; fourth, the provision of means integral with the hub of the fan for attaching the blades of the fan thereto and also of means whereby the said fan can be rotated independently of the shaft; and fifth, the provision of a fan with its hub which will be comparatively simple and inexpensive to manufacture, reliable and efficient in use, and readily applicable to its supporting shaft.

With the above and other objects in view, the present invention resides in the novel features of construction, formations, combinations, and arrangement of parts to be hereinafter more fully described, claimed, and illustrated in the accompanying drawings, in which

Figure 1 is a longitudinal sectional view of a blow fan having my improved hub applied thereto;

Fig. 2 is a similar view showing a different type of fan;

Fig. 3 is a transverse sectional view, taken on the line Y—Y of Fig. 2; and

Fig. 4 is a similar view, taken on the line X—X of Fig. 1.

Referring to the drawing by like characters of reference, throughout the several views, and more particularly to Figs. 1 and 4, the numeral 5 denotes in general a blow fan, comprising a housing 6 provided in its upper end with the oppositely disposed openings 7 through which passes a station-

ary shaft 8. This shaft 8 is supported in the brackets 9 and held against displacement, by the lock nuts 10 which are threaded on the ends of said shaft 8, engaging the brackets 9.

A hub 11 is rotatable upon the shaft 8 and comprises a cylindrical body 12, closed by the opposite ends 13 from which project concentric sleeves 14 and 15, which carry the drive pulleys 16 and 17. These pulleys 16 and 17 are of any preferred design, one being larger than the other, so the fan can be driven at different rates of speed. This hub 11 is provided with radial ribs 18 which extend from the cylindrical body 12 at suitable intervals and support the fan blades 19, which are united or otherwise secured thereto, as shown at 20.

A concentric bearing sleeve 21 is disposed within the hub 11 and has its central bore in alignment with and equal in size to the bores of the sleeves 14 and 15, and receives the before-mentioned shaft 8. The bearing sleeve 21 is held rigid within the hub 11 by the spaced webs 22, formed integrally upon the ends of the said sleeve 21 and cylindrical body 12 of the hub 11. The ends of the sleeve 21 are spaced from the ends 13, providing recesses 23 to receive the packings 24 which are held in position by the ends of the sleeve 21 and outer sides of the webs 22.

This peculiar formation produces an oil passage or chamber 25, arranged between the bearing sleeve 21 and cylindrical body 12 of the hub, and inner sides of the webs 22, which is provided with a threaded filling opening 26 disposed between the ribs 18. This opening 26 may be closed by the threaded plug 27.

It will thus be seen that oil from the passage 25 will work out through the packings 24 to the shaft 8 keeping the latter as well as the inner surfaces of the sleeves 14, 15 and 21, constantly lubricated, and the large bearing surfaces are properly distributed along the shaft.

Figs. 2 and 3 illustrate my fan hub 11 applied to a different type of fan. To accommodate this form of hub, the shaft 8 is provided with a collar 28 which contacts with the standard 29 in which it is held against rotation by the lock nut 30. A collar 31 is secured to the opposite end of the shaft 8 and is held against movement thereon by the set screws 32. This collar 31 prevents the

displacement of the hub 11 from the said shaft 8.

The pulleys 16 and 17, shown in Fig. 1, are also dispensed with and a drive pulley 33 is formed directly upon said hub 11 while an attaching flange 34 is formed thereon to which is bolted a casting 35 which fits on the sleeve 15 and supports the fan blades 36.

The hub 11 in this form of fan is similar to that described in Figs. 1 and 4, and further description thereof is deemed unnecessary as the same characters of reference will apply.

From the foregoing it will be apparent that a hub for fans is provided which will fulfil all of the necessary requirements of such a device in that a larger bearing surface is provided by the inner sleeve 21 and outer sleeves 14 and 15 for carrying the weight of the rapidly rotating fan and said sleeves are constantly and uniformly supplied with a copious supply of lubricant at all times, and under all conditions of service of the fan.

It should be understood that various minor changes in the specific details of construction can be resorted to within the scope of the appended claims without departing from or sacrificing any of the advantages of the invention.

It will also be seen that by providing the webs 22 at the outer ends of the inner concentric sleeve 21 of the hub, a firm support is provided for the sleeve 21 and the ends of said sleeve 21 are prevented from turning up so as to reduce the contacting surface of said sleeve 21 with shaft 8, and destroy the large bearing on the shaft for said hub of the fan, as provided in the present invention.

Furthermore by disposing the webs 22 at the outer ends of the sleeve 21 the hollow hub is readily cast without producing any such defects as blow holes, and insures a uniform

cooling of the casting and prevents cracks in the finished hollow hub.

45

What I claim is:

1. A fan comprising a fixed shaft, a hollow hub casing having an outer sleeve at each of its ends and an inner sleeve rotatable upon said shaft, a packing chamber within the casing surrounding and open to the shaft and adjacent to each of said end sleeves, a lubricant chamber in said casing surrounding the inner sleeve between the packing chambers and communicating with each of said packing chambers, whereby said lubricant can feed to the packing to lubricate the shaft and sleeves, fan blades carried by said hub and means for rotating said hub.

2. A fan comprising a fixed shaft, a hub casing rotatable thereon, means for rotating said hub upon the shaft, an outer sleeve formed upon each of the ends of the casing and engaging the shaft, an inner sleeve within the casing and engaging the shaft, said inner sleeve being spaced from the inner ends of the outer sleeves, webs connecting the ends of the inner sleeve with the interior of the hub casing and forming a continuous circular oil passage surrounding the shaft between said inner sleeve and inner side of the casing and webs, packings disposed between the inner ends of the outer sleeves and webs and engaging the shaft, whereby the oil or the like will be fed from the oil passage through the packings to the shaft between the inner and outer sleeves, said hub casing having an opening in communication with the oil passage, and a closure for said opening.

In testimony whereof I affix my signature in presence of two witnesses.

JOHN D. JONES.
